UNITED STATES PATENT OFFICE.

CLARENCE H. DAVIS, OF BENGE, WASHINGTON.

EMERGENCY-BRAKE.

1,120,796.

Specification of Letters Patent. Patented Dec. 15, 1914.

Application filed February 9, 1914. Serial No. 817,609.

To all whom it may concern:

Be it known that I, CLARENCE H. DAVIS, a citizen of the United States, residing at Benge, in the county of Adams and State of Washington, have invented new and useful Improvements in Emergency - Brakes, of which the following is a specification.

This invention relates to an improved operating means for emergency brake shoes of 10 that character wherein the shoe acts to apply emergency brakage when interposed between the rail and the truck wheel.

It is one of the objects of this invention to provide a mounting for emergency brake 15 shoes of this character, which will make the same applicable to trucks which pivotally or turnably support the car body, the device of my invention being mounted partly upon the truck and partly upon the car body in 20 such a manner that brakage can be applied even when the car is negotiating a curved stretch of track.

A further object of the invention is to provide an improved lever operating device 25 mounted to swing about an axis fixed with respect to the body, and so connected with the shoe mechanism as to render the latter operative by the former irrespective of the position which the truck causes the shoe and 30 its mechanism to assume with respect to the car body.

Other features and objects of the invention will be more fully described in connection with the accompanying drawings, and 35 will be more particularly pointed out in and by the appended claims.

In the drawings:—Figure 1 is a view in side elevation of a car illustrating the application of one form of the device of my 40 invention thereto. Fig. 2 is a longitudinal vertical section, with parts in elevation taken through a portion of the car near the front wheel of one of the trucks and showing the emergency shoe in an inoperative position. Fig. 3 is a view similar to Fig. 2 showing the shoe in an emergency braking position. Fig. 4 is a view in plan of the parts shown in Figs. 2 and 3. Fig. 5 is a perspective view of the emergency shoe and 50 its operating device. Fig. 6 is a sectional view on line 6—6 of Fig. 3. Fig. 7 is a sectional view on line 7—7 of Fig. 4. Fig. 8 is a detached view of an improved form of bell crank lever, showing the same in side 55 elevation, with parts in section. Fig. 9 is a

plan view of said lever showing the position of the same when the car is running on a straight stretch of track. Fig. 10 is a view similar to Fig. 9, showing the position which the lever assumes when the car is 60 rounding a curve.

Like characters of reference designate similar parts throughout the different figures of the drawings.

As shown, the car body is indicated at 1 65 and the truck frames at 2, the truck wheels being indicated at 3.

Emergency brake shoes are designated at 4 and the same are shaped on their lower faces 5 to slide on the tread of the rail, and 70 the said shoes are of that type in which the wheel rides up on the shoe when the latter is in an operating position. Thus the shoe 4 tapers, as at 6, and the incline terminates in a curved wheel tread engaging portion 7 75 having a radius equal to the radius of the wheel with which it cooperates. The shoe 4 is provided with a flange 8 for engagement with one side of the head of the rail 9 and the flange 8 is interrupted at its rear end 80 slightly in advance of the extremity of the tapered portion 6, as indicated at 10, so as to permit the wheel to ride up onto the shoe and prevent engagement of the wheel flange with the shoe flange 8. 85

Shoe hanging mechanism is provided, which comprises a yoke 11 having downwardly extending forks 12 in which a slotted shoe supporting guide 13 is hung. The shoe supporting guide 13 is provided with a slot 90 14 having retaining and preferably downwardly extending portions 15 and 16 offset therefrom. The shoe 4 is connected with and hangs pendent from two pairs of hanger straps 17 and 18, the upper ends of 95 which are connected by pins 19 and 20, which are adapted to seat in the offsets 15 and 16 and move rearwardly in the slot 14. When the shoe is in the position shown in Fig. 2, the pins 19 and 20 will seat in the 100 offsets 15 and 16, but when the yoke 11 is lowered so as to engage the shoe 4 with the rail 9, the pins 19 and 20 will be projected into the slot 14 and will be free to slide relatively to the member 13 as the latter advances. The slot is proportioned so that the wheel will run up onto the shoe 4 before the pin 19 reaches the end of the slot 14 and thereupon the shoe will advance with 105 the wheel and car. No strain is imposed 110

upon the hanger of the shoe at all during emergency action. When the car has been brought to a position of rest, it will either be positively backed off from the emergency shoes, or allowed to back off and this will return the yoke 11 and the member 13 to the position shown in Fig. 5, with respect to the pins 19 and 20, so that when the yoke 11 is elevated, the pins will be seated in the offsets 15 and 16, which will serve to effectively hold the emergency shoes in the desired advance position.

In order to at all times maintain the emergency shoes in operative relation with the truck wheels either when the same are running on a straight or curved stretch of track, I provide positioning or guiding means for the shoes, which are rigidly mounted upon the truck.

As illustrated, 21 designates a U-shaped frame which is secured to the truck frame at 22 and which extends forwardly with respect to the truck and closely adjacent the outside straps 17 and 18. Bars 23 extend closely adjacent the inside straps 17 and 18, and are secured at their forward ends to the U-shaped frame 21 and at their rearward ends to the truck frame 2. Thus it will be seen that this shoe guide mechanism on the truck frame will always maintain the shoes in predetermined relation with respect to the wheels, so that when they are lowered, they will always be in a position for correct operative engagement with the treads of the rails.

I provide guiding means for each brake shoe mechanism to guide the same in up and down adjustments and as shown, said guiding means comprises a frame composed of longitudinal members 24 connected by transverse members 25. The transverse members 25 are connected by hanger members 26, as will be clearly seen by reference to Fig. 4. The longitudinal members 24 are provided with guide arms 27, provided with guide openings for slidably receiving yoke bars 28 on the yoke 11, whereby the yokes 11 may be elevated or lowered.

It will be seen that the guide frame just described must also shift with the shoes on relative movement of the truck with respect to the body of the car, and therefore I movably support the guide frame mechanism upon the car body to afford relative movement therebetween.

As shown, tracks 29 and 30 are mounted on the car body and are arched in form about a center coincident with the turning axis of the truck with respect to the car body. The tracks 29 and 30 are of hollow construction and are provided with supporting flanges 31 and 32 on which rollers 33 and 34 are supported, the rollers 33 and 34 being preferably guided by the opposing walls of the hollow track structures. The rollers

are mounted on hangers 35 and 36, which are secured to the hanger members 26, whereby the guiding structure or frame is movably hung from the car body.

I will next describe the manner in which the brake shoes are raised and lowered.

An operating lever 37 is mounted to swing about an axis fixed with respect to the car body and shown in the form of a pivot 38 carried by a bracket 39. The lever 37 is provided with a hand grip pivoted thereto and indicated as a whole at 40, for operating a lock 41 to lock the lever in the position shown in Fig. 2, it being clear that it will be unnecessary to lock the lever when the same is in the position shown in Fig. 3. The lever 37 is connected by a link 42 with one end of an arm 43 of a bell crank lever, the other arm of which is indicated as a whole at 44. Said lever is mounted to swing about an axis, which is fixed with respect to the car body and which is shown in the form of a stud shaft 45 supported by a hanger 46 pendent from the car body.

The free end of arm 44 is connected with an elevating and lowering rod 47, which has its ends mounted in openings 48 in uprights 49 of yokes 11, as will be clearly seen by reference to Fig. 4. The bore of the arm 44, for receiving the rod 47, tapers outwardly toward its ends from a central crown annulus 50, which crown annulus is approximately the diameter of the rod so as to snugly fit the same. The outward tapers provide for engagement with the rod 47, without binding, irrespective of the angular disposition of the rod with respect to the arm bore, within certain limits. The position shown in Fig. 9 illustrates the mechanism when the car is running over a straight stretch of track, and the position shown in Fig. 10 illustrates the parts as they would appear when the car is rounding a curve.

Because of the fact that 45 is carried by the car body and that rod 47 not only moves into and from parallel relation with 45, but toward and away therefrom, extensibility is required between 47 and 45. Therefore, arm 44 comprises telescoping sections, one thereof comprising the head 51 and shank 52, formed in one piece, and the other of which comprises a socket 53 in which the shank 52 is slidable. The socket member 53 is pivoted, as indicated at 54, to the rigid terminal 55 of arm 43. Thus it will be seen that arm 44 is not only extensible in the direction of its length but that it is pivoted to swing about an axis angular to the axis 45 about which the bell crank lever turns as a whole, thereby providing for any angular disposition which the rod 47 may take with respect to the stud 45, and also any relative movement of these parts from each other.

It is believed that the advantages and utility of my invention will be clear from

the foregoing description, and while I have herein shown and described one specific form of my invention, I do not wish to be limited thereto except for such limitations as the 5 claims may import.

I claim:

1. In an emergency brake mechanism, a truck, a car body pivoted thereon, emergency brake shoes, devices pendently supporting said shoes, a frame for guiding said devices, means arched on the pivotal axis of the truck and carried by the body for movably supporting said frame, means carried by the truck for maintaining said 10 shoes in range for engagement with the tracks, and means movable about an axis fixed with respect to the car body for elevating and lowering said supporting devices in said guiding frame, substantially as 15 described.

2. In an emergency brake mechanism, a truck, a car body pivoted thereon, emergency brake shoes, devices pendently supporting said shoes, a frame for guiding said 25 devices, means arched on the pivotal axis of the truck and carried by the body for movably supporting said frame, means arched on the pivotal axis of the truck and carried by the body for movably supporting 30 said shoes in range for engagement with the tracks, and means for elevating and lowering said supporting devices in said guiding frame, substantially as described.

3. In an emergency brake mechanism, a truck, a car body pivoted thereon, emergency brake shoes, devices supporting said 35 shoes, a frame for guiding said devices into and out of operating positions and movably mounted on the car body, means carried by 40 the truck for maintaining said shoes in operative range with the tracks, and means for elevating and lowering said supporting devices in said frame, substantially as described.

4. In an emergency brake mechanism, a truck, a car body pivoted thereon, emergency brake shoes, devices supporting said 45 shoes, a frame movable horizontally abreast of the bottom of said car body for guiding 50 said devices into and out of operating positions, means for maintaining said shoes in operative range with the tracks, and means for elevating and lowering said supporting devices in said guiding frame, substantially 55 as described.

5. In an emergency brake mechanism, a truck, a car body pivoted thereon, emergency brake shoe devices, means movably carried by the car body for guiding said 60 shoe devices into and out of operative positions and means for maintaining said shoe devices in operative range with the tracks, substantially as described.

6. In an emergency brake mechanism, a 65 truck, a car body pivoted thereon, emer-

gency brake shoe devices, means movably mounted on the body for guiding said shoe devices in vertical movement, means carried by the truck for maintaining said shoe devices in operative range with the tracks, and 70 means mounted upon an axis fixed with respect to the body for elevating and lowering said shoe devices, substantially as described.

7. In an emergency brake mechanism, a car body, a truck pivotally supporting the 75 same, emergency brake shoes, and mechanism slidably mounted on the bottom of the car body transversely thereof and including means carrying said shoes and providing for horizontal movement of the shoes with respect to said means into operative relation between the wheels and tracks under frictional engagement between said shoes and the tracks, substantially as described.

8. In an emergency brake mechanism, a car body, a truck pivotally supporting the same, emergency brake shoes, and mechanism slidably transversely of the car body for suspending said shoes and including 80 shoe carrying means providing for horizontal movement of the shoes longitudinally of the car body into operative positions, substantially as described.

9. In an emergency brake mechanism, a truck, a car body pivoted thereon, emergency brake shoes slidably carried by the car body, and means for shifting said shoes into operative positions, substantially as described.

10. In an emergency brake mechanism, a truck, a car body pivoted thereon, emergency brake shoes slidably carried by the car body, and means mounted on the car body for shifting said shoes into operative 100 positions, substantially as described.

11. In an emergency brake mechanism, a truck, a car body pivoted thereon, emergency brake shoes, means for holding said shoes in range for engagement with the tracks, and means movable about an axis fixed with respect to the car body for raising and lowering said shoes and including a pivoted lever extensible in the direction of its length, substantially as described.

12. In an emergency brake mechanism, a truck, a car body pivoted thereon, emergency brake shoes, means for holding said shoes in range for engagement with the tracks, and means movable about an axis fixed with respect to the car body for raising and lowering said shoes and including a bell crank lever on such axis having an arm pivoted thereto and extensible in the direction of its length, substantially as described.

13. In an emergency brake mechanism, a truck, a car body pivoted thereon, emergency brake shoes, devices for holding said shoes in parallel relation with respect to each other, means for holding said shoes in operative relation with respect to the tracks, a 125

lifting rod connected with said devices, and a bell crank lever mounted to turn about a fixed axis on the car body and having one arm provided with an outwardly tapered bore for receiving said rod and being extensible in the direction of its length, substantially as described.

14. In an emergency brake mechanism, a truck, a car body pivoted thereon, emergency brake shoes, devices for holding said shoes in parallel relation with respect to each other, means for holding said shoes in operative relation with respect to the tracks, a lifting rod connected with said devices, and a bell crank lever mounted to turn about a fixed axis on the car body and having one arm pivoted and extensible in the direction of its length and provided at its free end with an oppositely tapered bore for engagement with said rod, substantially as described.

15. In an emergency brake mechanism, a truck, a car body pivoted thereon, emergency brake shoes, means for holding said shoes in range for engagement with the tracks, and extensible pivotal means carried by the car

body for raising and lowering said shoes, substantially as described.

16. In an emergency brake mechanism, a truck, a car body pivoted thereon, emergency brake shoes, means for holding said shoes in range for engagement with the tracks, and means carried by the car body and including a lever extensible in the direction of its length for raising and lowering said shoes, substantially as described.

17. In an emergency brake mechanism, a truck, a car body pivoted thereon, emergency brake shoes, means for holding said shoes in range for engagement with the tracks, and means movable about an axis fixed with respect to the car body for raising and lowering said shoes and including a pivotally connected lever, substantially as described.

In testimony that I claim the foregoing as my own, I hereby affix my signature in the presence of two subscribing witnesses.

CLARENCE H. DAVIS.
